BUILT-UP PRINT ROLL AND METHOD OF
MAKINGCharles F. Cooper, Torrington, Conn., assignor to
The American Brass Company, Waterbury,
Conn., a corporation of Connecticut

Application March 24, 1933, Serial No. 662,470

9 Claims. (Cl. 101—375)

This invention relates to new and useful improvements in printing means such as are used for printing textile fabrics, wall paper, oil cloth, linoleum and the like, and has particular relation to a print roll and method of making the same.

Heretofore, in practice these rolls have been substantially solid having only a longitudinal tapered opening therethrough to receive a mandrel. 10 Such rolls are expensive and when one etched or engraved design is to be discarded the roll is turned off in a lathe and another design etched or engraved thereon. When the roll has been reduced to a certain diameter or thickness it is no longer adapted for printing and although it still includes considerable metal it is merely sold as scrap. This 15 results in a waste of material and has other disadvantages. Furthermore, the larger sized solid rolls are very heavy and difficult to handle.

20 An object of the present invention is to provide a built up printing roll employing a minimum of material and reduced weight, and still will have great strength and rigidity. Rolls of large diameter or circumference can therefore be produced 25 with less metal. That is, with this built up construction I can reduce the amount of copper required per roll, thus reducing not only the original cost but also the tying up of considerable capital where large numbers of rolls are involved.

30 Another object is to provide a print roll including an inner structure or filler and an outer shell bearing the design and which shell may be replaced by a new shell on the filler when the old shell is no longer of use.

35 A further object is to provide an improved method of making built up print rolls, the method including steps whereby the inner structure or filler and the outer design bearing shell are firmly secured together against relative movement.

40 Other objects and advantages will become apparent from a consideration of the following detailed description taken in connection with the accompanying drawing wherein a satisfactory embodiment of the invention is shown. However, 45 it will be understood that the invention is not limited to the details disclosed but includes all such variations and modifications as fall within the spirit of the invention and the scope of the appended claims.

50 Fig. 1 is a view showing the parts of my improved printing roll assembled ready to be drawn through a die in accordance with the method of the present invention, the filler or inner structure of the roll being shown in elevation while the 55 outer shell and die are shown in section;

Fig. 2 is a longitudinal central sectional view through the roll when the latter is part way through the die;

Fig. 3 is a sectional view taken substantially along the line 3—3 of Fig. 2;

Fig. 4 is a detail sectional view on an enlarged scale, showing a portion of the assembly before passing through the die;

Fig. 5 is a similar view showing the same parts after they have been passed through the die; 10

Fig. 6 is a view similar to Fig. 4 showing a different portion of the shell before passing through the die; and

Fig. 7 is a view somewhat similar to Fig. 5 but showing this latter portion of the shell and filler 15 after passing through the die.

Referring in detail to the drawing, the improved built up printing roll includes an outer design bearing shell 10 and an inner structure or filler 11 carrying said shell. Filler 11 includes 20 a core 12 having a tapered opening 13 therethrough, the said opening being adapted to receive a similarly tapered mandrel onto which it is forced by hydraulic pressure, and within the opening the core includes a small key 14 adapted 25 to cooperate with a keyway in the mandrel (not shown). This core 12 may be especially prepared for its present function, or it may be an old printing roll which has been repeatedly turned down so that it is of too small a diameter for a 30 printing roll and so would ordinarily be sold as scrap metal.

The end portions of the core 12 may be reduced to provide shoulders 15 and 16 and the reduced end portions then threaded as at 17 and 18. 35 Next, a pair of filler rings 19 may be disposed on the core in spaced relation to one another and these rings are then shrunk on or otherwise rigidly secured to the core so as to move as a unit therewith. A filler ring 20 may now be 40 threaded onto the end portion 17 of the core and into abutting relation with the shoulder 15 and the end of the tube portion may be burred over with a dull tool as indicated at 33. This ring may be further secured in place as by locking pins 45 or screws 21 passing through the core and into the ring and it may also be soldered onto the threads, the idea being to use any suitable securing means which will fasten the ring to the core so it cannot become loosened in use. 50

A filler ring 22 may also be threaded onto the end portion 18 of the core and into engagement with the shoulder 16 after which the outer end of the tube portion 18 is burred over as at 23 with a dull tool whereby to permanently secure the 55

ring 22 in place. This ring may also be secured by pins 21 and soldered to the threads the same as ring 20. It will be understood that the various filler rings need not be assembled in any particular order since instead of first applying the intermediate rings 19 one of the end rings may be applied and then the intermediate rings may be applied and finally the second end ring. Also, either end ring may be applied first, and the rings need not necessarily be secured as described but any suitable means for effectively securing them in position may be used.

Each filler ring has its outer surface or edge roughened as by having its surface knurled or corrugated as indicated at 24 and the end rings 20 and 22 have their outer edges slightly beveled or tapered as best shown in Fig. 2 and from this figure it will be noted that the outer edges of these two rings are tapered in opposite directions with the smaller diameters toward the ends of the roll. When the inner structure or filler is completed as above described the outer tubular shell 10 is passed over the filler and the inner diameter of said shell is such that this may be easily accomplished although in Fig. 1 the clearance is exaggerated. As applied shell 10 at one end includes a reduced tapered portion 25 which embraces a head 26 carried by a rod 27 of a cylinder and piston construction (not shown).

At 28 is shown a die ring mounted in any suitable bed 29 and when the parts are arranged as shown in Fig. 1 any suitable means, as for example the cylinder and piston construction above referred to, is operated to draw the shell and the filler through the die 28. This reduces the diameter of the shell forcing it against the filler rings as illustrated in the left hand portion of Fig. 2. The pressure is such that portions of the material of the shell are forced into the grooves of the roughened or grooved outer edges 24 of the ring as shown at 30 in Figs. 5 and 7. Also, the edges of the rings 19, 20 and 22 are embedded in the metal of the shell as indicated in Figs. 5 and 7 as the shell is supported by these rings as they pass through the die, but the shell is not directly supported by these rings in the spaces between them and so the metal of the shell is forced inwardly somewhat between the rings as indicated. This results in the shell being rigidly secured to the filler whereby all of the parts move together as a unit and there is no danger of the shell or any of the supporting rings working loose in operation. After the assembly has been passed through the die the end portion 25 is cut from the shell as by severing it along the broken line 31 of Fig. 2.

The end rings 20 and 22 taper downwardly toward their outer surfaces and as the assembly is passed through the die the inner sharp ridge portion of each end ring is forced into the shell as best shown at 32 in Fig. 5. In this way, sharp abutting shoulders are provided at each end portion of the shell and longitudinal movement of the shell is prevented. Further, the pressing of the shell into the grooves 24 in the outer edges of the rings serves to rigidly secure the shell to the rings and to prevent any movement of the shell relative to the rings. The taper to the two end rings 20 and 22 provides a block of metal indicated between broken line 34, Fig. 5 and the surface of the ring which effectively prevents the ring moving outwardly.

It is especially to be noted that as the assembled structure is drawn through the die the effect of this drawing operation is the setting together of all parts in the structure. The result is a roll

which is practically a unitary or integral structure and which is of most unusual strength and rigidity. It is the combination of the construction and the drawing operation which gives these desired results.

It will be understood that Figs. 1, 2 and 3 show the roll on a very reduced scale and it is noted that Figs. 4, 5 and 6 show the portions of the roll at about half size. In an actual construction the shell 10 would be of stock approximately one-half inch thick and the filler rings are of stock approximately two inches thick. The completed roll would be in the neighborhood of 46 inches long and after being passed through the die may be turned down to a diameter desired (as for example, approximately 11 3/4 inches) and to give it a finished surface.

Any desired design may be engraved or etched in the outer surface of the shell 10. It is preferred that the entire filler or inner structure 11 be of non-ferrous metal, such for example as copper or a copper alloy, and that the shell 10 be of a similar metal. Where the filler is of iron and the shell of copper the parts have different coefficients of expansion and when the roll heats up in use the shell has a tendency to work loose from the filler. When the shell and filler are both of a similar metal, such as copper or a copper alloy, then there is no trouble regarding the shell working loose from the filler due to unequal expansion of the parts.

After the shell 10 has been used with one design engraved or etched thereon the shell may be turned down to remove the used design and another design may be etched or engraved in the shell. When the shell becomes too thin for further use it may be cut or stripped from the filler and a new shell applied as above described. From this it will be seen that the filler will remain in use indefinitely, it being only necessary to occasionally replace the shell and therefore the material wasted is reduced to a minimum. Further, there is a minimum of material used in producing a roll and the roll may be produced at relatively low cost since it does not involve the use of a great deal of material and since the shell is easily and quickly assembled on the filler. Attention is also directed to the fact that no extra or special parts are employed for securing the shell on the filler. There is a positive anchoring of assembly so as to give a rigid, solid structure. This built up roll is easier to handle than the solid roll because of the reduction in weight. Another feature is that during the operation of drawing the shell through the die the metal is worked or wrought and is therefore stronger and is of better grain than cast metal.

Having thus set forth the nature of my invention, what I claim is:

1. In a printing roll, a core, spaced filler rings carried by and rigid with said core, said rings having roughened outer edges, an outer shell of worked metal supported by said rings, and said shell including portions extending into the depressions in the roughened edges of the rings to form a rigid connection between the shell and the rings.

2. In a printing roll, a core, spaced filler rings carried by and rigid with said core, said rings having grooved outer edges, an outer shell of worked metal supported by said rings, and said shell including portions extending into the grooves in the rings whereby the shell is rigidly connected with the rings.

3. In a printing roll, a filler comprising a core

and spaced filler rings carried by and rigid with said core, said rings having roughened outer edges, an outer shell of worked metal on said rings, said shell including portions extending into the depressions in the roughened edges of the rings to provide a rigid connection between the shell and the rings, and said filler being of a metal having substantially the same coefficient of expansion as the metal of the shell.

10 4. In a printing roll, a filler comprising a core and spaced filler rings carried by and rigid with said core, said rings having roughened outer edges, an outer shell of worked metal on said rings, said shell including portions filling the depressions in the roughened edges of the rings to provide a rigid connection between the shell and the rings, said filler of non-ferrous metal and said shell being of a similar material.

15 5. In a printing roll, a filler comprising a core and spaced filler rings carried by and rigid with the core, said rings having roughened outer edges and the end rings being tapered with the smaller diameters toward the ends of the core, and an outer shell of worked metal closely embracing the edges of the rings so the metal of the shell extends into the depressions in the edges of the rings and the edges of the rings are sunk into the shell so as to rigidly anchor the shell to the

20 25 30 filler.

6. The method of forming a built up printing

roll, the same comprising providing a core, securing a plurality of filler rings on said core in spaced relation to one another, providing said rings with roughened outer edges, and then forcing a shell against the outer edges of the rings to force some of the material of the shell into the roughened edges of the rings.

5 10 7. The method of forming a built up printing roll, the same comprising providing a core, securing a plurality of filler rings on said core in spaced relation to one another, disposing a shell over said rings, and then passing the core, rings and shell through a die to draw the shell onto the rings.

15 8. The method of forming a built up printing roll, the same comprising providing a core, securing a plurality of filler rings on said core in spaced relation to one another, disposing a shell over said rings, and then reducing the diameter of the shell to have it tightly embrace the outer edges 20 of the rings.

25 9. The method of forming a built up printing roll, the same comprising providing a core, securing a pair of filler rings having oppositely inclined outer edges to said core, disposing an outer shell over said rings, and then forcing the shell against the rings to cause the latter to cut into the shell to rigidly secure the shell to the core.
